UNITED STATES PATENT OFFICE.

MEYER J. WOLF, OF NEW YORK, N. Y., ASSIGNOR TO WOLF, MUTTERPERL & COMPANY, OF NEW YORK, N. Y., A FIRM.

DESIGN FOR A HAND-BAG.

No. 37,683.

Specification for Design.

Patented Nov. 21, 1905.

Application filed September 18, 1905. Serial No. 279,055. Term of patent 7 years.

To all whom it may concern:

Be it known that I, MEYER J. WOLF, a citizen of the United States, and a resident of the borough of Manhattan, in the city and State of New York, have invented a new, original, and ornamental Design for a Hand-Bag, of which the following is a specification, reference being had to the accompanying drawings, forming a part thereof.

My new, original, and ornamental design for a hand-bag is shown in the accompanying drawings, in which—

I claim—

The ornamental design for a hand-bag, as shown.

MEYER J. WOLF.
